ATTORNEY

UNITED STATES PATENT OFFICE.

ALBERT AINSWORTH, OF SWARTHMORE, PENNSYLVANIA, ASSIGNOR TO BECKER,
SMITH & PAGE, OF PHILADELPHIA, PENNSYLVANIA, A CORPORATION OF PENN-SYLVANIA. DESIGN FOR EMBOSSED WALL-PAPER.

Specification for Design.

Patented Aug. 2, 1921.

58,527.

Application filed July 30, 1920. Serial No. 400,220. Term of patent 7 years.

To all whom it may concern:

Be it known that I, ALBERT AINSWORTH, a citizen of the United States, residing at Swarthmore, in the county of Delaware and State of Pennsylvania, have invented a new, original, and ornamental Design for Embossed Wall-Paper, of which the following is a specification, reference being had to the accompanying drawing, forming a part thereof.

The figure is a section of embossed wall paper showing my new design.

I claim:

The ornamental design for embossed wall paper as shown.

In testimony whereof I have hereunto set my name, this 28th day of July, 1920.

ALBERT AINSWORTH.
